US0D1017737S

(12) **United States Design Patent** (10) **Patent No.:** **US D1,017,737 S**
(45) **Date of Patent:** **** Mar. 12, 2024**

(54) **POWER TWISTER**

(71) Applicant: **Jianzhong Zhou**, Wuhan (CN)

(72) Inventor: **Jianzhong Zhou**, Wuhan (CN)

(**) Term: **15 Years**

(21) Appl. No.: **29/912,622**

(22) Filed: **Sep. 21, 2023**

(30) **Foreign Application Priority Data**

Jun. 15, 2023 (CN) 202330367866.6

(51) **LOC (14) Cl.** **21-02**

(52) **U.S. Cl.**

USPC **D21/679**

(58) **Field of Classification Search**

USPC D21/662, 679, 680, 682, 683, 684, 685,

(57) **CLAIM**

The ornamental design for a power twister, as shown and described.

DESCRIPTION

FIG. 1 is a perspective view of a power twister, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of a circled portion 9 thereof.

The broken lines shown are included for the purpose of illustrating portions of the power twister which form no part of the claimed design.

1 Claim, 9 Drawing Sheets
